US00D617463S

(12) **United States Design Patent**
Tokumoto et al.

(10) **Patent No.:** **US D617,463 S**
(45) **Date of Patent:** ** *Jun. 8, 2010

(54) **COMBINED MEDICAL PATCH AND PACKAGE**

5,820,622 A * 10/1998 Gross et al. 604/890.1

(75) Inventors: **Seiji Tokumoto**, Tsukuba (JP); **Tetsuji Kuwahara**, Tsukuba (JP); **Toshiyuki Matsudo**, Tsukuba (JP)

(Continued)

(73) Assignee: **Hisamitsu Pharmaceutical Co., Inc.** (JP)

EP 0 269 246 A2 6/1988

(**) Term: **14 Years**

(Continued)

(21) Appl. No.: **29/325,327**

Primary Examiner—Holly H Baynham

(22) Filed: **Sep. 29, 2008**

Assistant Examiner—Michelle E Wilson

(74) Attorney, Agent, or Firm—Holland & Hart LLP

(30) **Foreign Application Priority Data**

Apr. 16, 2008 (JP) D2008-009747

(51) **LOC (9) Cl.** **24-04**

(52) **U.S. Cl.** **D24/189**

(58) **Field of Classification Search** D24/189;
604/19, 20, 307, 304, 306; 602/41-59

See application file for complete search history.

(57) **CLAIM**

The ornamental design for a combined medical patch and package, as shown and described.

DESCRIPTION

FIG. 1 is a front perspective view of the combined medical patch and package, showing our new design;

FIG. 2 is a rear perspective view of the design illustrated in FIG. 1;

FIG. 3 is a front plan view of the design illustrated in FIG. 1;

FIG. 4 is a rear plan view of the design illustrated in FIG. 1;

FIG. 5 is a top plan view of the design illustrated in FIG. 1;

FIG. 6 is a bottom plan view of the design illustrated in FIG. 1;

FIG. 7 is a right plan view of the design illustrated in FIG. 1; and,

FIG. 8 is a left plan view of the design illustrated in FIG. 1. Portions of the drawings executed in broken lines in the various views are provided to illustrate environment and do not form a part of the claimed design.

1 Claim, 8 Drawing Sheets
